corporation of New York

Application December 21, 1943, Serial No. 515,113

12 Claims. (Cl. 266—2)

1

This invention relates to an apparatus for heat treating propeller blades and the like, and provides an apparatus which is less costly and more efficient for the purpose.

One of the objects of the invention is to avoid the difficulties encountered in prior practice of supporting the heated blade in a horizontal position as it is placed in the dies of a press for forming and quenching the same.

Another object of the invention is to avoid the requirement of an expensive press of large size and great power in confining the propeller blade during quenching.

A more specific object of the invention is to provide an apparatus for quickly removing a propeller blade from a heating furnace, conveying it to a quenching die and supporting the same during operation of the latter.

Another object is to provide a simple and inexpensive mechanism for operating and locking the quenching dies.

Another object is to provide an apparatus in which the propeller blade is suspended vertically throughout its heating and quenching operation.

Another object is to provide a simple indexing and operating mechanism for accurately locating the propeller blade in the dies.

Another object is to provide for the use of a number of individual furnaces with a single quenching apparatus to compensate for the different time rates for heating and cooling and avoid the difficulties inherent in employing a single large furnace unit.

Other objects will appear hereinafter in connection with the description of the embodiment of the invention illustrated in the accompanying drawings.

In the drawings:

Figure 1 is a side elevation of the apparatus with parts sectioned and showing a propeller blade in the furnace;

Fig. 2 is a front elevation of the quenching device with parts sectioned to show the toggle operation;

Fig. 3 is a top plan view of the apparatus;

Fig. 4 is a transverse horizontal section through the carriage;

Fig. 5 is a longitudinal section taken on line 5—5 of Fig. 4;

Fig. 6 is a transverse vertical section taken on line 6—6 of Fig. 5 and showing the indexing mechanism;

Fig. 7 is a transverse section through the quenching dies taken on line 7—7 of Fig. 2;

2

Fig. 8 is a detail front elevation of the face of the left-hand die;

Fig. 9 is a detail front elevation of the face of the right-hand die;

Fig. 10 is a transverse section through the dies taken on line 10—10 of Fig. 2 and showing the connections for cooling the blade shank;

Fig. 11 is an enlarged detail view partially in section showing the universal joint for suspending the propeller blade;

Fig. 12 is a control diagram showing a semi-automatic control for the apparatus; and

Fig. 13 is a schematic showing of a factory installation of a plurality of furnaces and a quenching device.

The apparatus is employed to heat a welded low alloy high strength hollow steel blade of substantially the finished shape, and then to quench the blade while holding it in shape. For this purpose, instead of directing a quenching fluid onto the surface of the blade, the latter is confined in substantially uniform contact with dies of high heat conductivity and through which a cooling medium is circulated. For the purpose of providing a uniform contact between the surface of the blade and the dies, a fluid pressure is applied internally of the hollow blade.

The apparatus comprises in general a heating furnace 1, a quenching device 2, and a conveyor mechanism 3.

The furnace 1 is preferably of the electric resistance type and is disposed like a well in the floor 4 of the shop with an opening 5 in its top for passage of the blade into and out of the furnace. Suitable heating elements 6 line the wall of the furnace and are connected through a transformer 7 to a source 8 of electric heating energy.

The quenching device 2 is disposed adjacent the furnace 1, and comprises a rigid upstanding frame 9 of generally horseshoe section having an opening 10 in the side facing the furnace for receiving a blade 11 by lateral movement of the latter. The frame 9 has a fixed die 12 with a recessed face 13 for receiving and confining one side of the twisted blade, and a movable die 14 with a similar complementary recessed face 15 for receiving and confining the other side of the twisted blade. The dies 12 and 14 are removable to provide for ready replacement with dies for different sizes and shapes of blades.

The die 14 is moved toward and away from the die 12 by means of a plurality of toggles 16 arranged parallel to one another and distributed one above the other at suitable spaced intervals in

the height of the die. For a die accommodating a blade of about six feet in length, the apparatus illustrated has five toggles 16, each having two links 17 and 18, pivoted to a common central toggle pin 19. The outer ends of the links 18 are pivoted to a set of fixed pins 20 secured in the frame 9. The outer ends of links 17 are pivoted to a set of pins 21 secured to the moving die backing or support 22.

The support 22 and its die 14 are mounted for movement toward and away from the die 12 in frame 9 which has slide plates 23 at the top and bottom for holding the dies in proper relative alignment.

The central toggle pins 19 pass through a pair of vertical toggle connecting arms 24 which secure the toggles together for simultaneous operation and serve to raise and lower the toggle pins 19 to operate the toggles. The arms 24 extend upwardly through the top of the frame and are connected by a pivot pin 25 to the short arm of a pivoted operating lever 26.

The lever 26 comprises two parallel bars pivoted on a fulcrum bracket 27 on top of the frame, and the long arm of the lever is connected at its outer end to a piston rod 28 of power cylinder 29 which is pivotally mounted on a bracket 30 on the side of the frame 9. A suitable adjustable stop 31 on frame 9 determines the limit of movement of lever 26 in spreading the toggles and closing the dies. This adjustment should allow the toggles to pass to dead center when the lever engages the stop to provide a lock for the toggles and prevent possible opening of the dies during quenching.

The frame 9 is reinforced by a plurality of horizontal plate ribs 32 embracing the frame around the back side and either welded thereto or cast integrally therewith. The frame has a top plate 33 which additionally secures the parts of the frame against deflection, the plate 33 having only the requisite slot 34 for receiving the support rod for the propeller blade 11. The base 35 of the frame extends across the opening 10 and secures the two sides of the frame directly together at the bottom. Heavy upright plates 36 are secured to top plate 33 and base 35 on opposite sides of the opening 10, and to the frame 9 for preventing deflection of the latter at intermediate points and to confine the dies.

The dies 12 and 14 have a series of ducts 37 distributed uniformly at a predetermined depth from the faces 13 and 15 for the purpose of transferring heat rapidly from the blade 11 to a cooling fluid such as water flowing through the ducts. Suitable pipe connections 38 are made to circulate water through the ducts 37.

The conveyor mechanism 3 comprises a pair of parallel horizontal spaced channel tracks 39 supported on top of the frame 9 and extending out over the furnace 1. A carriage 40 is supported by four rollers 41 riding in the channels 39 and is adapted to reciprocate between a position directly over the opening 5 in the furnace and a position directly over the recessed faces of dies 12 and 14 to transfer successive blades from the furnace to the quenching dies.

The carriage 40 is normally held in a position over the furnace opening 5 by means of a pair of cables 42 which are secured at one end to upstanding lugs 43 on top of the carriage, and pass in a reverse bend over fixed pulleys 44 on a cross member 45 at the forward end of the track 39, then through holes 46 in the carriage to the rear end of the track 39 and down over a pair of fixed

pulleys 47 to a weight 48. The weight 48 is sufficiently heavy to hold the carriage in place at the forward end of the track during lowering and raising of a propeller blade into and out of the furnace.

The carriage 40 has a rectangular pan-like frame, and the rollers 41 are secured to end extensions of the side members of the frame. Reinforcing pads 49 are laid in the bottom of each corner of the frame and an index pin 50 is suspended for vertical movement through the same from a similar pad 51 disposed at the top of each corner of the frame.

The propeller blade 11 is suspended tip-down from an elevator 52 which may have secured thereto a cover 53 for the furnace opening 5 and a suitable pipe connection 54 for supplying nitrogen or other suitable gas under pressure to the inside of the blade. A vent 55 provides for a measured escape of gas from the blade in purging the latter of oxygen.

The elevator 52 has a stem 56 extending downwardly and threaded into the shank of the blade to suspend the same during heating in the furnace. The stem 56 has a flange 57 at its upper end with a tapered lower surface adapted to rest upon a laterally movable sealing ring 58 supported in a cup 59 at the top of the elevator. This constitutes a universal joint which allows the blade 11 to hang vertical regardless of the fact that the elevator may not be vertical or of possible distortion of the same. At the same time, it allows for lateral movement of the stem in response to tolerances involved in positioning the blade in the dies.

The top of the elevator 52 is rectangular, and it has an index plug 60 with a tapered index hole for receiving the corresponding conical lower end of the respective index pin 50 at each corner when the elevator is raised to its upper position beneath the carriage 40.

Raising and lowering of the elevator 52 is accomplished by a pair of chains 61, each having one end removably secured to threaded lugs 62 in the top of elevator 52 and the other end secured to a cross member 63 at the rear end of the track 39. The chains 61 pass over sprockets 64 rotatably mounted on a bar 65 supported transversely between upstanding ears 66 on the sides of the carriage frame. The chains 61 pass horizontally from sprockets 64 to a series of sprockets 67 at the rear end of track 39. The sprockets 67 are arranged with two pair of fixed sprockets and two pair of movable sprockets, somewhat similar to block and tackle systems. The movable sprockets are secured to a header 68 on the upper end of the piston rod 69 of power cylinder 70. By utilizing the sprocket arrangement illustrated, the stroke of the piston in the cylinder 70 is only a fraction of the resulting vertical movement of elevator 52.

In operation, a downward movement of the piston rod 69 raises the elevator 52 from its lower position, where the blade 11 is being heated in the furnace, to its upper indexed position beneath carriage 40 where the blade 11 is entirely out of the furnace. Further downward movement of the piston rod 69 results in pulling the carriage 40 to the rear along track 39 and against the pull of cables 42 raising the weight 48 until the carriage engages a pair of adjustable stops 71 disposed adjacent track 39 to stop the carriage when the blade 11 is centered relative to the dies 12 and 14. After quenching of the blade 11 in the dies, the blade is withdrawn by raising piston

rod 69 and allowing weight 48 to pull the carriage forward to its normal position. The blade can then be removed and a succeeding blade secured to the lower end of stem 56 and lowered into the furnace for heating.

In order to prevent one side of the propeller blade 11 from engaging one of the dies prior to the other side engaging the other die, and consequent warpage of the blade with uneven heat treatment thereof, the elevator 52 has the pipe connection 54 and upper end of stem 56 secured in a transversely movable platform 72 slidably supported on two transverse rods 73 secured in the side plates of the elevator top. A central guide rod 74 carries a coil spring 75 which normally biases the platform 72 to one side of the elevator top. The platform 72 has a projection 76 extending through the side of the elevator and which is engaged by a push rod 77 during movement of die 14 to move the platform laterally with the die.

The movement of the platform 72 is approximately one-half that of the die 14 so that the blade 11 will be disposed about midway between the dies at all times during the die closing movement. For this purpose push rod 77 is operated by a toggle 78 having its center pin 79 connected to the lever 26 by a link 80. Operation of lever 26 in closing and opening the dies simultaneously operates the sliding of platform 72 in the elevator top.

The blade is accurately located in the dies by a camming action provided by the curvature of the shank 81 of the blade, the curvature of the tip index projection 82 of the blade and by cam blocks 83 disposed on opposite sides of die 12 about midway in the height of the die and entering corresponding recesses 84 in the die 14. As the dies close upon the blade 11, this cam action brings the blade into proper alignment with the die faces in the event there is any distortion of the blade from normal dimensions and shape or that the blade is not hanging truly vertical.

The proper quenching of the thick shank 81 is more difficult than that of the thin air foil section of the blade since the internal gas pressure is not effective to press the walls of the shank outwardly into tight contact with the dies. This is partially compensated for by employing a cushioned die insert 85 in each of the dies for engaging the shank on one side. The die inserts 85 are pressed outwardly by compressible rubber 86 or other suitable material disposed between the back of the inserts and the dies 12 and 14. When the inserts 85 engage the shank 81 of the blade during closing of the dies, the rubber 86 is compressed until the dies are completely closed, thereby providing a tight contact between the inserts and the shank.

The inserts 85 are preferably of copper and have grooved semi-cylindrical faces for receiving the shank.

The grooves 87 in the faces of the insert are interconnected and joined to a header 88 having a pipe connection 89 for supplying a cooling spray of water and air to the surface of the shank. In practice the actual rate of cooling of the shank end of the blade should be a little slower than that of the tip end.

The hydraulic control circuit illustrated in the diagram of Fig. 12 shows the manner of operating the apparatus. The power circuit for supplying fluid pressure to the power cylinders 29 and 70 includes a pump 90 and a fluid pressure

tank or accumulator 91 with a supply line 92 for cylinder 29 and a supply line 93 for cylinder 70. The supply line 92 has branches 94 and 95 leading to the opposite ends of cylinder 29 with a 5 multiple control valve 96 at their juncture for alternatively supplying fluid from pipe 92 to either end of the cylinder and simultaneously exhausting fluid from the opposite end of the cylinder. The supply line 93 has a three-way 10 valve 97 alternatively supplying fluid to cylinder 70 or exhausting fluid therefrom.

The gas supply circuit for the blade comprises a high pressure gas bottle 98 containing nitrogen or other suitable inert gas at a high pressure (normally around 2000 lbs. per sq. in.) and an auxiliary gas bottle 99 for receiving and storing a quantity of gas at the required operating pressure (normally around 300 lbs. per sq. in.). A pressure reducing valve 100 automatically feeds gas from bottle 98 to bottle 99 to maintain the required operating pressure in the latter.

A pipe line 101 leads from bottle 99 to two branch lines 102 and 103. Branch line 102 contains a reducing valve 104 which supplies a very 25 small flow of gas to the blade through pipe 54 during heating, the pressure of the gas in the blade being limited to only one or two pounds per square inch. Branch line 103 bypasses the valve 104 and contains a compressed air operated 30 quick opening valve 105 to supply the full gas pressure in bottle 99 to the blade when the latter is confined in the quenching dies.

The water circulation for cooling the dies is obtained from accumulator 91 through pipe 38 to the ducts 37 in the respective dies, one of the pipe connections being flexible to provide for relative movement between the dies.

The water spray for the shank is provided by pipe connections 89 from a spray-mix chamber 40 106 to the respective headers 88, one of the connections 89 being flexible to provide for relative movement between the inserts 85. The mixing chamber 106 in turn receives its air through check valve 107, manual pressure regulating valve 45 108 and control valve 109, from the air supply line 110 normally supplying air at about one hundred pounds per square inch pressure. The chamber 106 receives its water through a normally closed diaphragm control valve 111 from 50 the water storage tank 112, the latter being supplied through a check valve 113 from the ordinary tap water supply line 114.

The filling of tank 112 is controlled by the escape of air from the top of a float control chamber 115 through the normally open diaphragm control exhaust valve 116, the float 117 serving to cut off further escape of water through the valve 116.

The operation of the spray is effected by the 60 opening of control valve 109 by the operation of the die closing lever 26, admitting air under pressure to the mix chamber 106, as previously described. Air also passes from valve 109 through a check valve 118 to the top of float chamber 115 to force the water out of tank 112 into the mix chamber 106. For this purpose air pressure from valve 109 is admitted to valve 111 to open the same, and also to exhaust valve 116 to close the same.

An interlock may be provided between the control valve 109 and valve 105 to open the latter at the time the dies are closed.

When the blade is quenched, the valve 105 is closed and valve 55 opened to release the internal nitrogen pressure from the blade. Then the

control valve 108 is closed, thereby stopping the spray of water on the shank and closing valve 111 and opening valve 116.

If desired, an additional air blast may be applied to the stem 56 to rapidly cool the same and prevent its retained heat from effecting the quench of the upper end of the blade shank. This may be done by a branch pipe 119 leading from the line between pressure regulating valve 108 and check valve 107 to a stem spray nozzle 120.

The cycle of operation is substantially as follows:

The cycle starts with the blade 11 in furnace 1 where valve 104 feeds inert gas from bottle 99 slowly to the inside of the blade, allowing the gas to leak out of the vent valve 55 at the upper end of the blade supporting stem 56. The nitrogen in the blade during heating prevents oxidation of the metal inside.

When the blade 11 is heated to the required temperature for quenching, valve 97 is opened admitting power fluid from the accumulator tank 91 through line 93 to cylinder 70, thereby pulling piston rod 69 and header 68 downwardly and raising the elevator 52 until it indexes with carriage 40. Thereafter the downward movement of piston rod 69 is continued to pull the carriage 40, elevator 52 and blade 11 horizontally along track 39 until carriage 40 engages stops 71, indicating that the blade is centered between the dies 12 and 14. The weight 48 raises during the above described horizontal movement of carriage 40.

When the blade 11 is centered between dies 12 and 14, valve 96 is turned to admit power fluid from tank 91 to the upper end of cylinder 29 and to simultaneously exhaust fluid from the lower end of the cylinder to thereby operate the toggles 16 to move die 14 against die 12 and thereby confine the blade between the closed dies. During this closing of the dies, the push rod 77 operated by toggle 78 from lever 26 pushes the platform 72 transversely on the carriage at a rate approximating one-half the rate of movement of die 14 to maintain the blade midway between the dies at all times and prevent early contact of only a portion of the blade. During the final stage of the die closing operation, the blade is cammed into the recesses in the die faces 13 and 15 by means of the cam blocks 83 engaging the edges of the blade, the action of the inserts 85 upon the shank, and the action of the die faces on the tip index 82.

After the toggles 16 pass dead center, the stop 31 is engaged by the lever arm 26 to prevent further operation of the toggles, and the control valve 109 is automatically opened. The valve 105 in branch line 103 is opened wide to quickly admit the full pressure of the gas in bottle 99 to the inside of blade 11 and press the sides of the blade outwardly against the confining die surfaces.

At the same time air passes from control valve 109 through valves 108 and 107 to mix chamber 106. Air also passes from control valve 109 directly to the valves 111 and 116, opening the former and closing the latter. In addition to this, air passes from control valve 109 through check valve 118 to the top of the chamber 115, thereby forcing the water from chamber 115 and tank 112 into the mix chamber 106. The air and water in mix chamber 106 is forced through connection 88 to the header 88 in inserts 85 where the mixture is sprayed onto the shank of the blade.

During the closing of the dies and preferably prior to final closing, water is admitted from ac-

cumulator 91 through pipe 38 to the ducts 37 in the respective dies, and a continuous flow of water is maintained through the ducts during cooling of the blade.

The blade is ordinarily left in the dies for about five minutes, until a proper quench is assured, after which valves 105 and 109 are shut and the gas pressure is released from the inside of the blade by the manual bleeder valve 55. Valve 96 is then turned to admit power fluid from tank 91 to the lower end of cylinder 29 and to simultaneously exhaust fluid from the upper end of the cylinder, to thereby operate the toggles 16 in a direction effecting opening of the dies. During this opening movement, the rod 77 will be gradually retracted by toggle 78, allowing the spring 75 to return the platform 72 to normal conveyor position with the blade spaced midway between the open dies.

After separation of the dies, valve 97 is operated to allow a limited upward movement of piston rod 69 and header 68, effected by weight 48 pulling the carriage 40 forward on track 39. The forward movement of carriage 40 brings the blade out of the quenching apparatus 2 to a position where it can be readily removed from stem 56 and a new blade secured in place for lowering into the furnace.

The control above described is largely semi-automatic. The amount of manual control and of interlock of the several operations is purely a matter of choice.

In actual practice, the quenching apparatus 2 and its conveyor mechanism 3 are mounted on a track 121 extending adjacent to a line of furnaces 1, as illustrated in Fig. 13. In this way a single quenching apparatus can handle the output of six or seven furnaces, and by reason of its equal proximity to each furnace when in operation, the quenching of the blades from successive furnaces will be substantially equal and uniform. The time cycle of operation of the quenching apparatus is only a small part of the time cycle for heating a blade in a furnace. The quenching apparatus 2 can be moved from one furnace to another and be kept in operation almost constantly. By employing a plurality of small individual furnaces instead of a single large one, the production line can be kept in operation during times when a furnace is shut down for repairs or for other reasons.

The invention may have various embodiments within the scope of the accompanying claims.

I claim:

1. In an apparatus for treating propeller blades and the like, a quenching device comprising vertically disposed relatively laterally movable quenching dies having complementary die faces for receiving and confining a blade, means automatically adjustable laterally in correlation to the closing of the dies upon the blade for suspending a blade therein, means for closing said dies upon the blade, and cam means for straightening said blade relative to said die faces as the latter close upon the same.

2. In an apparatus for treating propeller blades and the like, a quenching device comprising a vertically disposed fixed die member, a vertically disposed laterally movable die member, said die members having complementary faces for receiving a blade suspended therebetween, a carriage for transferring a blade to said dies, a platform in said carriage for carrying the blade, and means providing limited transverse movement of

said platform relative to said carriage to position the blade accurately in said dies.

3. In an apparatus of the class described, a carriage for transferring a blade horizontally from one position of treatment to another, an elevator suspended from said carriage for raising and lowering the blade, means for indexing said elevator with said carriage when said elevator is in uppermost position, a platform in said elevator for carrying the blade, and means providing limited transverse movement of said platform relative to said elevator and carriage to position the blade accurately in a vertical direction and in two horizontal directions.

4. In an apparatus of the class described, a hollow vertical stem for securing the shank of a propeller blade and the like to suspend the same, said stem having a flanged head adapted to rest on a horizontally movable ring to support the head in a laterally floating manner for die quenching metal articles.

5. In an apparatus of the class described, a quenching die for receiving a hollow heated article made up in part of rigid walls and in part of flexible walls, a cushioned die insert for receiving the rigid walls of the article, and means for pressing the flexible walls of the article against the face of the die to provide a uniform heat conductive contact between the article and die to effect quenching of the article.

6. In an apparatus for treating propeller blades and the like, a quenching device comprising vertically disposed relatively laterally movable dies having complementary die faces for receiving and confining a blade, means for suspending a blade therein, and means for closing said dies upon the blade, said suspending means comprising a hollow vertical stem for securing the shank of the blade and having a flanged head adapted to rest on a horizontally movable ring to support the head in a laterally floating manner for centering the same in the quenching dies.

7. In an apparatus for treating propeller blades and the like, a quenching device comprising vertically disposed relatively laterally movable dies having quenching die faces for receiving and confining a blade in direct contact conductive of uniform conduction of heat from substantially the entire surface area of the blade for quenching the same, and means including a slideable carriage disposed above the dies and automatically adjustable laterally with respect to the path of travel of the carriage in synchronism with the closing of the dies upon the blade for suspending a blade between the dies.

8. In an apparatus for treating propeller blades and the like, a quenching device comprising vertically disposed relatively laterally movable dies having complementary die faces for receiving and confining a blade, a slideable carriage disposed above said dies and automatically adjustable laterally with respect to the path of travel of the carriage in synchronism with the closing of the dies upon the blade for suspending a blade between the dies, and means disposed to close the dies upon the blade including means to move said slideable carriage a predetermined distance in relation to the travel of the dies.

9. In an apparatus for treating propeller blades and the like, a quenching device comprising a vertically disposed fixed die member, a vertically disposed die member laterally movable toward and away from said fixed die member, said die members having complementary faces for receiving a blade suspended therebetween, means dis-

posed above the dies to suspend a blade between the open die faces including a slideable carriage automatically adjustable laterally with respect to the path of travel of the carriage in synchronism with the closing of the dies upon the blade, and means disposed to operate said movable die member to open and close said dies including means to simultaneously move said slideable carriage a predetermined distance in relation to the travel of said movable die.

10. In an apparatus for treating propeller blades and the like, a quenching device comprising a vertically disposed fixed die member, a vertically disposed die member laterally movable toward and away from said fixed die member, said die members having complementary faces for receiving a blade suspended therebetween, means disposed above the dies to suspend a blade between the open die faces including a slideable carriage automatically adjustable laterally with respect to path of travel of the carriage in synchronism with the closing of the dies upon the blade, means disposed to operate said movable die member to open and close said die, and means operatively connected to said die moving means to simultaneously move said slideable carriage a predetermined distance to prevent contact of the blade with either face until final closing position.

11. A quenching device for treating propeller blades and the like, comprising a rigid upstanding frame of substantially horse-shoe shape having a vertically disposed opening through one side thereof, a vertically disposed fixed die member at one side of said opening and a vertically disposed die member at the other side of said opening and laterally movable toward and away from said fixed die member within said frame, said die members having complementary faces for receiving a blade suspended therebetween, a series of toggles disposed between and pivotally secured to said movable die member and said frame and spaced apart and distributed vertically behind said die member, and means disposed to operate said toggles simultaneously to open and close said dies.

12. A quenching device for treating propeller blades and the like, comprising a rigid upstanding frame of substantially horse-shoe shape and having a vertically disposed opening through one side thereof for receiving work to be quenched, a plurality of vertically distributed horizontally extending reinforcing ribs embracing a major portion of said frame to secure the latter against deflection, a vertically disposed fixed die member and a similarly disposed laterally movable die member within said frame and having complementary faces for receiving a blade suspended therebetween, a series of toggles disposed between and pivotally secured to said movable die member and said frame, said toggles being spaced apart and distributed vertically behind said die member, and means for operating said toggles to open and close said dies.
